BALL-BEARING CLAMP TO HOLD
STRAIGHTEDGE ON A DRAFTING
BOARD

Dale D. Spoor, Kalamazoo, Mich.

Application December 13, 1946, Serial No. 716,020

2 Claims. (Cl. 33—80)

1

The present invention relates to improvements in ways and means expressly constructed and adapted to accommodate and shiftably mount a straight edge on a drafting table, drawing board or the like, it being the primary object of the invention to structurally, functionally and otherwise improve upon known types of clamps in this field of invention.

Another object of the invention has to do with novel straight edge clamps and means for mechanically and slidably mounting the same on a drawing board, this in a manner to adjustably situate the straight edge in proper operative relation to the drawing surface of said board whether the latter be in a horizontal, vertical or intermediate drafting position.

A further object of the invention resides in the provision of a structural adaptation which lends itself particularly applicable and commercially satisfactory and efficiently adaptable to requirements of the trade and the user under virtually all conditions and circumstances.

A still further object of the invention, generally speaking, is to improve upon and reduce the number of elements and parts which enter into the complete combination, thereby not only increasing resultfulness and the efficiency of the structure as a whole, but also rendering same less costly to manufacture, and to otherwise simplify factors of assembling, sale and reliable usage.

In addition to the above and considered from a structural and functional point of view, an added object of the invention is to provide simple grooved bars, these being attached securely to transverse end portions of the drawing board, the same serving as tracks, and further providing effective devices to accommodate special slide brackets, the brackets functioning as carriages on which the end portions of the straight edge are detachably and adjustably mounted.

Other objects, features and advantages will become more readily apparent from the various views of the accompanying sheet of drawings.

In the drawings, wherein like numerals are employed to designate like parts throughout same:

Figure 1 is a fragmentary view illustrating a corner portion of a drafting or drawing board, parts being in section and elevation, said view showing one of the clamps and complementary features thereof.

Figure 2 is an end elevation with portions broken away and shown in section and other parts removed, of Figure 1, observing the latter in a direction from right to left.

2

Figure 3 is a top plan view of the structure shown in Figure 1.

Figure 4 is a reduced view showing a drafting table, this provided with the invention herein under advisement.

Figure 5 is a fragmentary end elevation of the structure seen in Figure 1 with certain parts removed.

Figure 6 is a perspective of a clip forming a part of the track means.

Reference being had first to the complete illustration in Figure 4, we observe an ordinary type of drafting table, same including a stand or base A and a tiltable top, such as will hereinafter be referred to either as a drafting or drawing board B. The straight edge is denoted by the numeral 8 and is of a length greater than the length of the board B, the end portions thereof being provided with centralized attaching and adjusting slots 9. Both ends of the straight edge are slotted and adjustably and slidably mounted on the drawing board. In this connection, and inasmuch as the structure at each end of the board is the same, a description of the structure at one end will suffice for both.

In carrying out the specific principles of the invention a bar 10, substantially rectangular in cross sectional form, and of a length corresponding to the width of a drawing board is provided.

As shown in Figure 1 said bar 10 is secured, by screws or equivalent fastening means 11, to the coacting end portion of the board. It is preferably positioned so that the bottom surface thereof is substantially flush with the corresponding bottom surface of said board. The top and bottom surfaces of said bar have shallow longitudinal grooves 12 and 13 respectively and these serve as track ways. Thus, the grooved bar functions as a simple track and lends itself admirably

well adapted to a simple and expedient slide bracket 14. Said bracket 14 comprises a channel-shaped portion 15 which functions as a shoe and which is mounted upon and shiftable along said track. The particular manner in which the shoe is saddled upon the track is brought out in Figures 1 and 2 and in reference to Figure 1 it will be seen that the upper and lower flanges of said shoe are provided with holes 16 and 17 properly seated to accommodate anti-friction

balls 18 and 19. The web portion of the shoe is provided with appropriate set-screw 20 which serves, whenever necessary or desired, to bind and fasten the shoe in a predetermined as well as an established position. In this connection it is well to point out that by making the parts under precision dimensions, sufficient retentive

action may be attained between the shoe and track to cause the shoe to remain relatively stationary when placed in a set position and without necessarily having to tighten the set-screw 20. The upper portion of the bracket or shoe is of general L-shaped form as at 21 and the horizontal or upper limb of this is provided with an upstanding screw-threaded stud 22. The inner end portion of the stud is formed with a substantially rectangular block-like guide and assembling element 23 which serves to snugly accommodate the coacting slot 9.

The numeral 24 designates a washer surrounding the stud, 25 a coiled spring, and 26 a knurled nut on the stud which serves to properly tension and regulate the spring. It is thus that the slotted end of the straight edge is detachably and adjustably assembled.

Reference being had now to Figure 2, the numeral 27 designates a cleat or clip which is secured by a fastening 28 to one end of the bar in a manner to close the adjacent open ends of the track way grooves. The opposite ends of said grooves are closed in at the time of manufacture.

It will be evident that by slidably bracketing the end portions of a straight edge to the transverse ends of a drawing board and saddling the brackets over simple track bars, a structural adaptation is thus provided whereby the straight edge is constantly on the board and is ever in readiness for use when needed and for placement at an out-of-the-way position when not needed. The use of ball bearing brackets, and tracking supporting means provides what is believed to be an exclusive and ideal means accomplishing the ends desired.

Changes in shape, size, materials and rearrangement of details and parts may be resorted to in actual practice, so long as they do not depart from the spirit of the invention or the scope of the appended claims, as is well understood.

What is claimed as new is:

1. An anti-friction slide construction of the class shown and described comprising a board having a flat top susceptible of use, if desired, as a drafting board, a bar removably screwed to one marginal edge portion of said board, the bottom of said bar being flush with the bottom of said board and the top of said bar being on a plane below the top of said board, a one-piece longitudinally shiftable adaptor bracket including a channel-shaped portion constituting a shoe, said shoe partially encasing, fitting over, and being slidable back and forth on said bar, said shoe embodying top and bottom flanges provided with freely rollable ball bearings, the top and bottom surfaces of said bar being provided with open-ended channels providing trackways for said ball bearings, the latter being seated in said trackways, said brackets including an L-shaped upstanding portion having its horizontal limb parallel to and above the top flange of the shoe and located on

a plane substantially flush with the top surface of said board and equipped with an upstanding screw-threaded stud carrying a nut to accommodate, if desired, a member which may be slidably mounted for shiftable movement on said board, and end cleats removably mounted on the opposite end portions of said bar and closing the open ends of the respective channels.

2. An anti-friction slide structure of the class shown and described comprising a board having a flat top susceptible of use, as desired, as a drafting board, a bar detachably screwed to one marginal edge portion of said board, said bar being substantially rectangular in cross section, the top and bottom surfaces of said bar having open-ended channels providing trackways for freely rollable ball bearings, the bottom surface of said bar being flush with the bottom of the board and the top of said bar being on a plane below the top surface of said board, a one-piece longitudinally shiftable adaptor bracket including a channel-shaped portion having top and bottom flanges and a bight connecting said flanges, said channel-shaped portion partially encasing and fitting over and being slidable back and forth on said bar and constituting an anti-friction slide, anti-friction balls mounted for free rotation in the top and bottom flanges and situated in and rollable back and forth in said trackways, said bracket including an inverted L-shaped portion having horizontal and vertical limbs, the horizontal limb being in spaced parallelism above the top flange of said shoe and being in a plane substantially flush with the flat top of said board and provided with an upstanding screw-threaded stud, an assembling and retaining nut carried by said stud, a set screw carried by said bight and releasably engageable with a coacting surface of said bar, and a pair of end cleats removably mounted on the opposite end portions of said bar and having their respective end portions lined up with and closing the end portions of said channels.
